FOREIGN PATENT DOCUMENTS

EM 015065117 * 9/2024

Primary Examiner — S. Bryan Reinholdt, Jr.

(74) Attorney, Agent, or Firm — Epstein Drangel LLP;
Robert L. Epstein(57) **CLAIM**

The ornamental design for a drinking spout substantially as shown and described.

DESCRIPTION

FIG. 1 is a Top Front Right Side Isometric view of the drinking spout of the present invention;
FIG. 2 is a Bottom Rear Left Side Isometric view thereof;
FIG. 3 is a Front elevation view thereof;
FIG. 4 is a Rear elevation view thereof;
FIG. 5 is a Left Side elevation view thereof;
FIG. 6 is a Right Side elevation view thereof;
FIG. 7 is a Top plan view thereof; and,
FIG. 8 is a Bottom plan view thereof.

1 Claim, 6 Drawing Sheets(56)
